(57) **CLAIM**

The ornamental design for the folding knife, as shown and described.

DESCRIPTION

FIG. 1 shows a front perspective view of a folding knife in the open position;

FIG. 2 shows a front perspective view of the folding knife in the closed position;

FIG. 3 shows a rear perspective view of the folding knife in the open position of FIG. 1;

FIG. 4 shows a rear perspective view of the folding knife in the closed position of FIG. 2;

FIG. 5 shows a front elevation view of the folding knife in the open position of FIG. 1;

FIG. 6 shows a front elevation view of the folding knife in the closed position of FIG. 2;

FIG. 7 shows a rear elevation view of the folding knife in the open position of FIG. 1;

FIG. 8 shows a rear elevation view of the folding knife in the closed position of FIG. 2;

FIG. 9 shows a top plan view of the folding knife in the open position of FIG. 1;

FIG. 10 shows a top plan view of the folding knife in the closed position of FIG. 2;

FIG. 11 shows a bottom plan view of the folding knife in the open position of FIG. 1;

FIG. 12 shows a bottom plan view of the folding knife in the closed position of FIG. 1;

FIG. 13 shows a right side elevation view of the folding knife in the open position of FIG. 1;

FIG. 14 shows a left side elevation view of the folding knife in the open position of FIG. 1;

FIG. 15 shows a left side elevation view of the folding knife in the closed position of FIG. 2; and,

FIG. 16 shows a right side elevation view of the folding knife in the closed position of FIG. 2.
